CLAIM

The ornamental design for a butter stick, as shown and described.

DESCRIPTION

FIG. 1 is a top, front, left side perspective view of a butter stick;

FIG. 2 is a top plan view thereof, the bottom plan view being a mirror image thereof;

FIG. 3 is a front elevation view thereof, the back elevation view being a mirror image thereof;

FIG. 4 is a left side elevation view thereof; and,

FIG. 5 is a right side elevation view thereof.

The dot-dash broken lines illustrated in the butter stick surfaces define the bounds of the claim, forming no part thereof. The evenly-spaced broken lines at the breaks in the drawings illustrate portions of the butter stick that form no part of the claim. Any portion of the article between those breaks forms no part of the claimed design.
